[57] **CLAIM**

The ornamental design for a therapeutic weight transfer sling, as shown.

DESCRIPTION

FIG. 1 is a perspective view of a therapeutic weight transfer sling, showing my new design;

FIG. 2 is a front elevational view thereof;

FIG. 3 is a rear elevational view thereof;

FIG. 4 is a right side elevational view thereof; and,

FIG. 5 is a left side elevational view thereof.

The broken line showing of the body is for illustrative purposes only and forms no part of the claimed design.
